DESIGN FOR A JACKET OR SIMILAR ARTICLE

Theo Schaumer, Los Angeles, Calif.

Application October 2, 1940, Serial No. 95,557

Term of patent 7 years

To all whom it may concern:

Be it known that I, Theo Schaumer, a citizen of the United States and a resident of the city of Los Angeles, in the county of Los Angeles and State of California, have invented a new, original, and ornamental Design for a Jacket or Similar Article, of which the following is a specification, reference being had to the accompanying drawing, forming part thereof, in which:

Fig. 2 is a rear view thereof.

I claim:

The ornamental design for a jacket or similar article, substantially as shown.

THEO SCHAUMER.
